UNITED STATES PATENT OFFICE

THEODORE D. JONES, OF LOS ANGELES, CALIFORNIA

SHAVING MUG

Application filed June 1, 1929. Serial No. 367,777.

This invention relates to improvements in shaving mugs of the type employed by barbers and others for the making of lather for shaving.

5 In the usual construction of shaving mugs a cake of soap is placed in the mug and rests on the bottom and therefore when the brush is used for mixing up the lather a much greater amount of soap is used than is actually necessary.

It is the object of this invention to produce a shaving mug which shall be so constructed that the soap instead of resting on the bottom of the mug is located in a recess 15 to one side of the mug and near the upper end thereof so as to leave the mug itself available for the formation of the lather. By this means the soap will not be unnecessarily consumed as the user will employ only 20 the amount of soap necessary to produce the lather and in this way the waste of soap is prevented.

It is another object of this invention to produce a mug that shall be so constructed 25 that by its use lather containing a greater amount of water than ordinary lather can be produced. This object is obtained by providing the bottom of the mug with a plurality of spaced upwardly extending pins 20 which cooperate with the bristles of the brush so as to produce a better and more desirable lather with the minimum amount of soap.

It is another object of this invention to 35 produce a mug of such construction that it can be preheated with boiling water. The radiation of the heat from the preheated body of the mug accelerates the formation of the lather and facilitates the production 40 of the stiff lather which is so desirable in shaving. The construction of the mug which permits the preheating consists in a lateral recess on one side of the mug which serves to hold the soap and which therefore makes 45 it possible to partly fill the mug with hot water without having the latter come in contact with the soap.

The above and other objects which may 50 become apparent as the description proceeds are attained by means of a construction and

an arrangement of parts that will now be described in detail, reference for this purpose being had to the accompanying drawings in which the preferred embodiment of the invention has been shown, and in which:

Fig. 1 is a top plan view of the mug; and

Fig. 2 is a section taken on line 2—2, Fig. 1, the soap being shown in place on the supporting shelf.

In the drawings reference numeral 1 represents the wall of the mug and 2 the bottom thereof, while 3 indicates the handle. One side of the mug is provided with a laterally extending recess or shelf whose outer wall has been indicated by reference numeral 4 and whose bottom has been designated by numeral 5. The end walls of this recess have both been designated by reference numeral 6. The upper surface of the bottom 5 of the recess is substantially flat and is provided with a number of upwardly extending pins 7 which are adapted to project into the soap which has been shown in place thereon in Fig. 2 and has been designated by reference numeral 8. When a piece of soap is put into the recess and pressed downwardly against the upper surface of the bottom thereof the pin 7 will securely hold it in the position shown.

The upper surface of bottom 2 is provided with a plurality of spaced pins 9. These pins cooperate with the brush in the formation of the lather. When the brush is moved back and forth across the bottom, pins 9 will extend in between the bristles and it has been found that by the addition of pins the length of time that the lather must be agitated for the production of a lather of the necessary stiffness, can be greatly decreased and that the lather will contain more water in proportion to the amount of soap than when it is formed by agitation in contact with the soap, or by agitation in a mug having a smooth bottom.

This mug is also especially well adapted to be maintained in a sterile condition as the body of the mug can be very readily sterilized by boiling water or by the use of a disinfecting solution without effecting the

soap, as the latter is supported near the top of the mug, as shown.

In the operation of producing lather, the brush is first applied to the soap, after which it is agitated in contact with the pins 9 and if more soap is necessary the brush is again brought into contact with the soap and in this manner only the amount of soap actually necessary is used.

10 From the above description it will be seen that I have produced a shaving mug of a novel construction that is especially well adapted for use by barbers as it can be easily maintained in a sterile and sanitary condition and which permits better lather to be formed with the least expenditure of soap and energy and which is also very economical with respect to the amount of soap used.

15 The mug can be made from the ordinary materials now employed and the pins 7 and 9 can be moulded integral with the body of the mug.

20 Having described my invention what I claim as new is:

25 1. A shaving mug comprising a receptacle member having projections extending from the bottom thereof for cooperation with the bristles of a shaving brush in producing a lather, said mug having a cake soap receiving compartment adjacent to the top thereof, and means in said compartment for positively gripping a soap cake and retaining it therein.

30 2. A shaving mug comprising a receptacle member having projections extending from the bottom thereof for cooperation with the bristles of a shaving brush in producing a lather, said mug having a cake soap receiving compartment adjacent to the top thereof, and projections in said compartment for gripping a soap cake and retaining it therein.

35 In testimony whereof I affix my signature.

THEODORE D. JONES.
